MACHINE FOR CORRUGATING METAL STRIPS

Filed June 27, 1923

Inventor
Abraham Goldberger
By His Attorney
Cornelia C. Pittinger

Patented Nov. 11, 1924.

UNITED STATES PATENT OFFICE.

ABRAHAM GOLDBERGER, OF NEW YORK, N. Y.

MACHINE FOR CORRUGATING METAL STRIPS.

Application filed June 27, 1923. Serial No. 647,971.

To all whom it may concern:

Be it known that I, ABRAHAM GOLDBERGER, a citizen of the United States, and a resident of the borough of Manhattan, city, county, 5 and State of New York, have invented certain new and useful Improvements in Machines for Corrugating Metal Strips, of which the following is a specification.

This invention relates to a machine for 10 corrugating or shaping metal strips and, more particularly, to a machine for corrugating strips in suitable forms for use in making automobile radiators and apparatus of similar character.

15 Strips of this character are customarily formed by passing the strips between a pair of intermeshing corrugated rollers having their peripheries shaped to give the proper form to the strips. In the manufacture of 20 radiator elements the strips are corrugated centrally and provided with edges offset to space the central corrugated portions sufficiently to form a water channel when a pair of strips are placed in the proper position 25 on each other. These rolls are usually built up of sets of narrow section rollers or gear dials or wheels mounted closely adjacent each other on a common axle, each section roller or gear having a surface shaped to 30 correspond with that desired for a corresponding portion of the strip being formed.

An object of my present invention is to provide an apparatus for shaping metal strips having an improved guide for the 35 strips of metal passing to the rollers for pressing into the desired configuration.

Other objects of the invention are to provide a set of rollers of the type indicated with a stationary feeding guide which will 40 permit the strips of metal to be easily fed to, and removed from the rolls, and to permit a ready adjustment of the sizes and shapes of the rolls.

With these and other objects in view, the 45 invention comprises the apparatus described and set forth in the following specification and claims.

The various features of the invention are 50 illustrated in the accompanying drawings in which:

Figure 1 is a sectional elevation through a corrugating roll apparatus embodying a form of my invention taken on line 1—1 of Fig. 2.

55 Fig. 2 is a front elevation of the apparatus illustrated in Fig. 1.

Fig. 3 is a side view of a corrugated spacing strip for automobile radiators showing the type of corrugations produced in the apparatus shown in Figs. 1 and 2. 60

Fig. 4 is a side view of a pair of strips shaped to form a water channel when placed side to side as indicated, and,

Fig. 5 is a detail view of a modified form of guide spacing and supporting rod forming part of the invention. 65

In the present invention the strips of sheet metal are guided into position between the rolls by means of a pair of stationary guides positioned one at each end of the set of rolls 70 and held firmly against the ends of the rolls at their line of contact. The guides are supported on a frame on which the rolls are also supported and, as the guides do not have any movement they enable the strips 75 of metal to be easily inserted into position to be engaged by the rolls and pulled therebetween. No guides need be provided at the exit side of the set of rolls so that the shaped strips are delivered without contact 80 with any means which might interfere with their easy delivery from the rolls.

Referring more particularly to the accompanying drawings, the invention is illustrated as applied to a pair of upper and 85 lower rolls 10 and 12 mounted on axles 14 and 16, respectively, supported in a frame 18. The roll 10 is formed of a middle corrugated roll section 20, which may provide a central corrugation to the strips as indicated at 22 in Fig. 4, for example, and a pair of end roll sections or gears 24 and 26 which may impress corresponding corrugated portions on strips of metal 27 as indicated at 28 in Fig. 4. The roll 12 is 90 formed in a similar manner and meshes with the roll 10 as at 30, the rolls being separated sufficiently to provide a clearance and backlash between the teeth of the rollers equal to the thickness of the sheets of metal 100 passing therethrough.

The length of the rolls is equal to the width of the sheets of metal passing therethrough and, for the best work it is necessary that the edges of the sheets be in substantial alignment with the edges of the rolls. To this end, a pair of guide plates 32 and 34 are mounted on a front wall 36 of the frame 18 and have their faces flat against the ends of the rolls at the place where the 105 rolls intermesh. As the guides are stationary they permit the sheets of metal to be 110

readily inserted and guided to a position where they may be engaged by the intermeshing rolls and drawn therethrough.

The guides are preferably made of flat plates of curved shape so that they may be attached by means of screws 38 at one end to the end edges of a mounting plate 40 of the same width as the length of the rolls and at their other ends may extend to the end faces of the rolls. The mounting plate may then be attached to the front 36 of the frame 18 by means of bolts 42 passing through slots 44 in the front 36 to enable the plate to be adjusted to the position of the rolls. The upper portions of the guides are also preferably spaced and guided by means of a rod 46 immediately in front of the rolls and extending between side plates 48 and 50 of the frame 18 and through holes in the guide plates of sufficient diameter to slide freely over the rod. The guides are spaced on the rod 46 by means of a collar 52 positioned between the guides and by clamping the guides against this collar by means of nuts 54 and 56 threaded on the rod 46 against the outer faces of the guides.

With this arrangement a collar, or combination of collars is required for each different width of rolls, and the adjustment of the guides for slight changes in width is limited. In the modified form of rod shown in Fig. 5, the collar is dispensed with and replaced by a nut 58 on the opposite face of the guide from the nut 54 or nut 56 and by the movement of these nuts back or forth on the rod, the distance of the guides from each other may be adjusted very accurately. The rod may be attached to the side walls 48 and 50 of the frame 18 by means of nuts 60 as indicated in Fig. 2, or by means of a screw 62 as indicated in Fig. 5 or by other suitable means.

The various roll sections may be clamped in position on the axles 14 and 16 in any suitable manner, as, for example by means of nuts 64 and 66 threaded on the shafts 14 and 16, respectively, at one end of the rolls and pressing the rolls against suitable stops at the opposite ends of the rolls. The shafts 14 and 16 are journaled in bearings 68 and 70 respectively, on the side walls 48 and 50 and the distances or spacing of the axles is adjusted by means of bolts 72 spanning the bearing supports or in any other suitable manner.

The rolls may be of any surface configuration to accomplish the bending of the strips to the desired form. For example the strips may be bent into the form shown at 22 and 28 in Fig. 4 to form water conduits or channels or into the form shown at 74 in Fig. 3, to form spacing elements for the water channels by a suitable replacement of the rolls. The rolls may be driven in any suitable manner.

As changes of construction could be made within the scope of my invention it is intended that all the matter contained in the above description or shown in the accompanying drawings be interpreted as illustrative and not in a limiting sense.

Having thus described my invention what I claim and desire to secure by Letters Patent is:

1. Apparatus of the type described which comprises, a pair of intermeshing corrugated rolls, a supporting framework for said rolls, a pair of guides fixed to the front portion of said framework and extending rearwardly to overlap with the opposite ends of said rolls at the place of intermeshing, and a rod extending through the upper portions of said guides and arranged to hold said guides in spaced relation.

2. Apparatus of the type described which comprises, a pair of intermeshing corrugated rolls, a supporting frame for said rolls, a pair of guides fixed to the front portion of said frame and extending rearwardly to overlap the opposite ends of said rolls at the place of intermeshing, a rod extending through the upper portions of said guides, and means threaded on said rod for holding said guides in adjusted spaced relation to each other and said rolls.

3. Apparatus of the type described which comprises, a pair of intermeshing corrugated rolls, a supporting frame for said rolls, a mounting plate on the front portion of said frame, a pair of guides bolted to opposite ends of said mounting plate and extending rearwardly to overlap the opposite ends of said rolls at their place of intermeshing, a rod extending through the upper portions of said guides and mounted in the sides of said frame, and means on said rod for holding said guides in spaced relation and in position relative to said rolls.

ABRAHAM GOLDBERGER.
